PIPE CUTTER

Thorvald Petersen, Erie, Pa., assignor to Reed Manufacturing Company, Erie, Pa., a corporation of Pennsylvania

Application November 13, 1940, Serial No. 365,476

4 Claims. (Cl. 30—102)

Pipe cutters are usually provided with a plurality of rollers, some carried by the shank, others carried by some adjusting means, and at least one of these has a cutting edge. It is desirable to have these rollers related so they are so spaced that the thrusts may be more or less balanced between the rollers. It is desirable to space the rollers for large pipe far enough apart to engage the pipe at fairly widely spaced points on the pipe. Such a spacing is too great for a small pipe. In consequence it has been common to provide several pipe cutters adapted for different sizes of pipe. The present invention is designed to provide a cutter with different roller spacings, the arrangement permitting of opposing these rollers having the different spacing with an adjustable roller in proper relation to such spacing. Further, this is accomplished in a simple way by providing a swinging mounting for the adjustable roller, utilizing the various angles of the swinging mounting to properly oppose the spaced rollers. Features and details of the invention will appear from the specification and claims.

A preferred embodiment of the invention is illustrated in the accompanying drawing as follows:

Fig. 1 shows a side elevation partly in section of a cutter with a pipe of comparatively large size in position for cutting.

Fig. 2 a similar view with the cutter operating on a smaller pipe.

Fig. 3 a section on the line 3—3 in Fig. 1.

1 marks the shank of the cutter, 2 the nose of the cutter. The shank and nose are preferably of channel form. As shown, non-cutting rollers 3, 4 and 5 are arranged in the nose and journaled on pins 6 extending through the walls of the channel in the nose. The rollers 3 and 4 are widely spaced and preferably in line with the extension of the shank. Rollers 4 and 5 are less widely spaced. A line joining the centers of the rollers 4 and 5 is at an angle to a line joining the centers of rollers 3 and 4.

A swinging arm 7 is mounted between the walls of the channel of the shank and is pivoted on a pin 8 secured in the walls. A cutter roller 9 is carried by the swinging arm by means of a journal pin 10. The arm has a curved surface 11 which is engaged by the adjusting screw 12, the curve 11 being such as to provide a directly opposing surface to the screw with each position of the arm. The screw extends through the usual nut 13 on the shank and the outer end of the screw is provided with a handle 14 for operating the screw.

A spring 15 has a coil 16 wrapped around a pin 17. The swinging arm 7 has a projection 18 forming a bell crank with the arm 7 and the projection 18 is engaged by one end 19 of the spring, the opposite end 20 of the spring being braced on the bottom of the channel so that the arm 7 is yieldingly held against the screw 12.

When a large pipe such as 21 is to be cut the arm 7 is swung back so that a line through the cutter and tangent to the arc described by the cutter as it swings about its center of support will pass between the rollers 3 and 4, thus the cutter roller 9 directly opposes these widely spaced rollers providing a proper relation between the rollers for this size of pipe, and this spacing may be used for pipes slightly larger and slightly smaller than the pipe 21 providing the usual range of a cutter with three wheels. When a small pipe such as 22 is to be cut the arm 7 is positioned so that the tangent to the swinging arc of the wheel 9 passes between the wheels 4 and 5 so that the rollers 4, 5 and 9 are in proper relation for this small pipe. Again, a pipe slightly smaller or larger than the pipe 22 may be cut with the wheels 4, 5 and 9 so that quite a large range of sizes may be accommodated in the single pipe cutter, the largest size accommodated by rollers 4 and 5 and being the next smaller than the smallest pipe properly accommodated by the rollers 3 and 4.

The swinging arm also provides a convenient means for mounting the adjustable roller which, as shown, is the cutter wheel. In the present structure this arm is mounted between the walls of the channelled shank so that a firm mounting for the cutter is provided, and at the same time the structure involves very little frictional resistance to the proper adjustment by means of the screw.

While I have shown but one cutter wheel I do not wish in the broader phases of the invention to be limited to the use of non-cutting wheels in conjunction therewith.

What I claim as new is:

1. In a pipe cutter having a shank, a nose on the shank, an adjusting means, a plurality of rollers in the nose providing pairs with different spacings, the combination with said shank, nose, adjusting means and rollers of a swinging arm actuated by the adjusting means and pivotally mounted with relation to the shank, a roller on the arm, the arm placing its roller in position to oppose a pair of rollers widely spaced at one angle of the arm and to oppose a pair of rollers less widely spaced at another angle of the arm,

at least one of the rollers having a cutting edge.

2. In a pipe cutter having a channeled shank, a nose on the shank, adjusting means, a plurality of rollers in the nose providing pairs with different spacings, the combination with said shank, nose, adjusting means and rollers of a swinging arm actuated by the adjusting means and pivotally mounted between the walls of the channeled shank, a roller on the arm, the arm placing its roller in position to oppose a pair of rollers widely spaced at one angle of the arm and to oppose a pair of rollers less widely spaced at another angle of the arm, at least one of the rollers having a cutting edge.

3. In a pipe cutter having a shank, a nose on the shank, a plurality of rollers in the nose providing pairs with different spacings, the combination with said shank, nose and rollers of a swinging arm pivotally mounted on the shank, a roller on the arm, the arm placing its roller in position to oppose a pair of rollers widely spaced

at one angle of the arm and to oppose a pair of rollers less widely spaced at another angle of the arm, at least one of the rollers having a cutting edge.

5 4. In a pipe cutter having a shank, a nose on the shank, a plurality of rollers in the nose providing pairs with different spacings and an adjusting screw in the shank, the combination with said shank, nose and rollers of a swinging arm pivotally mounted in the shank, a roller on the arm, the arm placing its roller in position to oppose a pair of rollers widely spaced at one angle of the arm and to oppose a pair of rollers less widely spaced at another angle of the arm, at least one of the rollers having a cutting edge, the arm being provided with an arcuate surface abutting the adjusting screw making the tangent at a point of contact to the screw at right angles to the axis of the screw in its different adjustments.

THORVALD PETERSEN.
